US0D1110721S

(12) **United States Design Patent** (10) **Patent No.:** **US D1,110,721 S**
(45) **Date of Patent:** **** Feb. 3, 2026**

(54) **TRUNK**

(71) Applicant: **G.T. LINE - S.R.L.**, Valsamoggia (IT)

(72) Inventor: **Massimo Tonelli**, Bologna (IT)

(73) Assignee: **G.T. LINE—S.R.L.**, Valsamoggia (IT)

(**) Term: **15 Years**

(21) Appl. No.: **29/926,680**

(22) Filed: **Jan. 31, 2024**

(30) **Foreign Application Priority Data**

Jul. 31, 2023 (EM) 015029715-0001

(57) **CLAIM**

The ornamental design for a trunk, as shown and described.

DESCRIPTION

FIG. 1 is a perspective view of a trunk, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof;

FIG. 9 is a front perspective view thereof with a portion of the trunk in an extended position;

FIG. 10 is a perspective view thereof with a portion of the trunk in the extended position;

FIG. 11 is a perspective view of the trunk, showing my new design in a second embodiment;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is a rear perspective view thereof.

The broken lines illustrate portions of the trunk and form no part of the claimed design.

1 Claim, 18 Drawing Sheets
